DESCRIPTION

(51) **LOC (10) Cl.** 03-01

FIG. 1 is a front perspective view of the travelkey pocket
passport format for printed material showing my new design,
which is a booklet containing a cover with text pages, whereas
the cover has a third panel leaf are part of the claimed design
and folded inward between the inside front cover and page 1
of the text. The short broken lines on the third panel leaf
represent a die-cut slot through the paper for the insertion of
a plastic room key.
